(57) **CLAIM**

The ornamental design for a connector for fire pipe, as shown and described.

DESCRIPTION

FIG. 1 is a perspective view of the connector for fire pipe;

FIG. 2 is a front view;

FIG. 3 is a rear view;

FIG. 4 is a left side view;

FIG. 5 is a right side view;

FIG. 6 is a top plan view; and,

FIG. 7 is a bottom view.

The broken lines are for illustrative purposes only and form no part of the claimed design or a specified embodiment thereof.
